US00D440549S

(12) **United States Design Patent** (10) Patent No.: **US D440,549 S**
Scorrano (45) Date of Patent: ** Apr. 17, 2001

(54) **DIGITAL COMPACT DISC STEREO RADIO
PLAYER**

(75) Inventor: **Vincent Scorrano**, Kowloon (HK)

(73) Assignee: **Aspen Marketing, Inc.**, Evergreen, CO
(US)

(**) Term: **14 Years**

(21) Appl. No.: **29/118,724**

(22) Filed: **Feb. 14, 2000**

(51) LOC (7) Cl. **14-01**

(52) U.S. Cl. **D14/168**; D14/214; D14/156

(57) **CLAIM**

The ornamental design for a digital compact disc stereo radio player, as shown and described.

DESCRIPTION

FIG. 1 is a perspective view of the digital compact disc stereo radio player of my invention;

FIG. 2 is a front elevational view thereof shown in an alternate position;

FIG. 3 is a front elevational view of the stereo radio player of my invention, shown separately for clarity of illustration;

FIG. 4 is a back elevational view of the stereo radio player of my invention;

FIG. 5 is a right side elevational view of the stereo radio player of my invention;

FIG. 6 is a left side elevational view of the stereo radio player of my invention;

FIG. 7 is a top plan view of the stereo radio player of my invention;

FIG. 8 is a bottom plan view of the stereo radio player of my invention;

FIG. 9 is a front elevational view of the compact disc player of my invention, shown separately for clarity of illustration;

FIG. 10 is a rear elevational view of the compact disc player of my invention;

FIG. 11 is a right side elevational view of the compact disc player of my invention;

FIG. 12 is a left side elevational view of the compact disc player of my invention;

FIG. 13 is top plan view of the compact disc player of my invention;

FIG. 14 is a bottom plan view of the compact disc player of my invention;

FIG. 15 is a front elevational view of the speaker of my invention, shown separately for clarity of illustration; the other speaker being identical;

FIG. 16 is a rear elevation view of a speaker of my invention;

FIG. 17 is a right side elevational view of a speaker of my invention;

FIG. 18 is a left side elevational view of a speaker of my invention;

FIG. 19 is a top plan view of a speaker of my invention; and,

FIG. 20 is a bottom plan view of a speaker of my invention.

FIG. 2 is on an enlarged scale.

1 Claim, 10 Drawing Sheets
